UNITED STATES PATENT OFFICE

THEODOR SENDLER, OF STETTIN, GERMANY

MOP

Application filed June 21, 1932, Serial No. 618,426, and in Germany July 9, 1931.

This invention relates to a mop having a divided head for washing, wiping or otherwise treating surfaces, such as floors, walls, etc.

8 In mops of this nature the parts of the head are furnished with a readily absorptive, sponge-like facing, by means of which the water, etc., is applied to the surface under treatment and, after the facing of absorptive material has been squeezed out, may again be removed.

15 It is the primary object of this invention to generally improve on mops of this type so that the head of the mop may be introduced below relatively low articles of furniture and into inaccessible corners, and so that the mop may be readily squeezed out without contaminating the hands.

20 This is accomplished by the fact that the handle of the mop is connected to the head so as to be oscillatory to the extent of approximately 180° about the same and to be capable of adjustment in any desired position. Further, there is provided on the movable handle 25 a device connected with the parts of the head, which device may be actuated in any position of the handle, and by means of which the parts of the head may be tightly pressed together and again moved apart.

30 Other objects and advantages of the invention will become apparent as the description proceeds.

The invention will now be described more fully with reference to the accompanying drawings, which illustrate the invention in two possible forms of embodiment.

35 Fig. 1 is an elevational view of one form of embodiment of the mop in the position of use.

40 Fig. 2 shows the head of the mop during the operation of squeezing out the water.

Fig. 3 is an end view of the mop, and

45 Fig. 4 is a plan view, the handle being shown in section.

50 Fig. 5 is an elevational view, partly in section, of a modified form of embodiment of the mop,

Fig. 6 being a plan view of the head of the mop according to Fig. 5, and

55 Fig. 7 an elevational view of the mop ac-

cording to Fig. 5 during the operation of squeezing out the water.

Fig. 8 is a section taken on the line VIII—VIII of Fig. 5.

In the form of embodiment according to 55 Figs. 1—4 the head of the mop consists of two block-like portions *a* and *b*, which are composed of wood or any other suitable material. The two blocks *a* and *b* are pivoted by means of pins *p* to a transverse holder comprising 60 two metallic yoke members *c*. These yoke members are widened out in box-like fashion at *f*, and these box-like sections are firmly connected together at the apices of the two yoke members. On the pins *p* there may be 65 provided coil springs *p''* having the opposite ends fixed to the blocks *a*, *b* and the yoke members *c*, by means of which the blocks *a* and *b* are moved into the position according to Fig. 1, and which springs are tensioned in 70 the position of the blocks according to Fig. 2. To each block *a* and *b* there is detachably secured a sponge-like pad or other absorptive facing or fitting *d*, which may consist of rubber sponge or any other convenient material 75 which will apply the water or other cleansing agent to the surface under treatment and again absorb the superfluous liquid when squeezed out.

At the point where the two yoke members 80 *c* are connected together there is pivotally connected by means of a pin *n* a sleeve or socket *h*, which serves for the attachment of the lower end of the handle *i*.

For the purpose of locking the handle *i* in 85 those particular inclined positions in relation to the head which are usually required hooks *k* are provided on the yoke members *c* engaging in eyes *k'* on the socket *h*.

To each block portion *a* and *b* there is secured on the two end faces an actuating means, which may consist, for example, of a flexible wire *m*. The points of attachment *m'* are so disposed that by the application of a tensile force to the wires the blocks *a* and *b* 95 may be moved about their pins *p* in the manner indicated in Fig. 2. The wires *m* from all four end faces of the blocks *a* and *b* are passed through holes *e* into the box-like enlargements *f* of the yoke members *c* and about 100

the pin *n* with which the socket *h* is pivotally secured to the yoke members *c* or enlargements *f*. The wires which proceed from the end faces of each block *a* or *b* may be twisted above the pin *n* to form a strand. The two strands are conducted upwards through the handle *i*, which is constituted by a tubular member, and project out of the upper open end thereof. Outside of the handle the two strands are connected to a ring *o* or other suitable grip, so that when the grip is pulled the wires *m* are subjected to a tensile force, whereby the blocks *a* and *b* may be moved out of the position in Fig. 1 into that according to Fig. 2. The wires *m* may also be conducted along the outside of the handle, in which case the same are then held against the handle by means of clips, eyes or the like. It is not essential that the wires are conducted right up to the upper end of the handle, and an opening might be provided laterally in the handle at a suitable point between its two ends, through which opening the wires are allowed to emerge for connection with the grip. If desired, small rollers may be provided in or on the handle for guiding the wires.

Preparatory to cleaning a surface the head of the mop is immersed in water in the position shown in Fig. 1, whereby the sponge-like facings or fittings absorb water in the usual manner. If the mop is then passed backwards and forwards with the facings of absorptive material engaging the surface to be cleaned, the water is pressed out and the surface provided with a plentitude of water, so that the dirt is loosened and picked up by the facings *d*. The head of the mop with the facings, may naturally be immersed in the water as often as desired. For the purpose of again removing the water from the surface the parts *a* and *b* are compressed over a pail or other receptacle in the manner shown in Fig. 2 by pulling the handle *o*, and accordingly the wires *m*. By reason of this compression the water contained in the facings or fittings is squeezed out so that only very little remains therein, and the facings or fittings are capable of absorbing water anew, the grip *o* thereupon being released, whereby the blocks *a* and *b* return under the action of the springs *p* on the pins *p* into the position shown in Fig. 1. The relatively dry mop is then applied to the surface under treatment, and the facings *d* absorb the superfluous moisture. The mop is theretupon again squeezed out in the manner described by pulling the grip *o*, the mop being held for this purpose over the pail or other receptacle employed. This operation may be repeated as often as necessary.

In the form of embodiment according to Figs. 5-7 the head of the mop also comprises the two block portions *a* and *b*, which are furnished with the sponge-like facings or fit-

tings *d*. The facing of each block is composed of two parts, between which there is an intermediate space *t*.

In this embodiment the transverse holder for the head of the mop consists of two straight plates *c*, *c*', on which the two blocks are mounted in oscillatory fashion by means of the threaded bolts *p*', *p*'. The threaded bolts *p*' are all situated in the one horizontal plane. At the centre between the two ends of the plates *c*' there is pivotally connected by means of pins *n* a fork or U-shaped member *c*'', which possesses a socket or sleeve *h*'. In this socket or sleeve there is secured the lower end of the handle *i*', which is capable of being moved together with the fork *c*'' to the extent of 180° about the pins *n*. To each plate *c*' there is pivoted a somewhat resilient arm *k*' having a plurality of holes. The arms *k*' are bent in such fashion that the same are capable of engaging with one of the holes over a pin *g*, which is secured laterally to the fork *c*''. By means of this arrangement the fork *c*'', and accordingly the handle *i*', may be locked in various inclined positions in relation to the head of the mop.

At the centre of each block *a*, *b* there is provided a recess, which is open towards the opposite side of the blocks *a* and *b*, and serves in each case for the reception of a toothed segment or segment gear *r* or *r*'. The toothed segments are so arranged that their centre points coincide with those of the pins *p*' and that of each segment the part bearing the teeth projects into the space *t* intermediate the facings *d*'. The teeth of the two segments *r* and *r*' for the blocks *a* and *b* are placed in engagement with each other, so that when the one segment with the appertaining head portion is caused to rotate the second segment is also moved about its centre and moves the appertaining head portion.

For secure attachment of the segments *r*, *r*' in the blocks *a* and *b* there is mounted firmly on each an arm *s*, which passes through a transverse boring in the head, and is furnished on the outside of the block with a thread. On the thread there is screwed a nut *s*', which is securely tightened against the outside of the block, and by means of which the arm *s* of the segment and the appertaining block are tightly connected.

To the one segment *r*' there is secured an arm *v*, which projects with its free end into the space between the two head portions *a* and *b*. To the free end of the arm *v* there is pivoted by means of a pin *v*' a rod *w*, which passes approximately vertically upwards in the space between the two parts *a* and *b*, and is pivotally connected by a pin *x* with a tie-rod *y*. This tie-rod *y* is conducted along the handle *i*', preferably through the sleeve *h*'. The sleeve *h*', which firmly encompasses the handle *i*', is bulged out for this particular purpose, as shown in Fig. 8, so that a

guideway is produced for the rod y . In this guideway the rod y may be moved backwards and forwards without obstruction. If the rod is lifted or pulled by means of the bent grip z , it also moves the rod w , and through the medium of the arm v thus rotates the segment r' with its block b about the pins p' . The segment r' moves the segment r , and the two blocks a and b thus being brought into the position shown in Fig. 7.

To prevent accidental displacement of the rod y the same may also be embedded outside of the sleeve h' in an open groove in the handle i' , and at the upper end adjacent the grip z may possess a stud z' , which snaps into a recess in the handle i' . The rod y , which is composed of iron, possesses a sufficient natural resiliency to permit of withdrawal of the stud z' from the recess in the handle i to permit actuation of the rod y .

The manipulation of the mop according to Figs. 5-8 is similar to that as described in connection with Figs. 1-4. By reason of the means y, w, v in conjunction with the toothed segments r, r' the blocks a and b may be compressed in exactly the same fashion as with the corresponding device shown in Figs. 1-4.

It will be understood that no restriction is made to the specific forms of embodiment shown in the drawings, which are shown merely by way of example, and that various modifications are quite possible within the meaning of the above description and the annexed claims without departing from the spirit of the invention.

What I claim as new and desire to secure by Letters Patent is:

1. In a mop, a divided mop head, absorptive facings on the parts of the said head, a transverse holder to which the single parts of the said head are each pivoted per se so as to be capable of oscillation, and means for causing the said parts to move together for compressing the said facings and to return to the normal position.

2. In a mop, a mop head comprising a pair of blocks, absorbent material fixed to the working faces of the blocks, a pair of yoke members connected together intermediate their ends and pivotally carrying the blocks of the mop head between the ends, a handle pivotally mounted on the connected portions of the yoke members, flexible members connected at one end to the mop head blocks and extended longitudinally along the handle, a manipulating grip connected to the ends of the flexible members opposite to the ends connected to the blocks whereby a pulling force exerted on the flexible members through the grip will actuate the blocks about their pivotal supports on the yoke members and position the absorbent materials into compressing contact, and springs coiled about said pivotal supports of the blocks on the yoke members with the free ends thereof fixed to

the blocks and yoke members to normally urge the blocks to position with the absorbent materials extending in the same plane out of contact with each other upon the cessation of said pulling force on the flexible members.

3. In a mop, a mop head comprising a pair of blocks, absorbent material fixed to the working faces of the blocks, a holder pivotally supporting the blocks in spaced relation to each other in their operative positions, a handle mounted on the holder, meshing segment gears carried by the blocks, and means mounted on the handle and connected to the segment gears adapted to actuate the gears and the mop head blocks to position the absorbent materials into impinging relation.

4. In a mop, a mop head comprising a pair of blocks, absorbent material fixed to the working faces of the blocks, a holder adapted to pivotally support the blocks in spaced relation to each other in their operative positions, a handle mounted on the holder, segment gears carried by the blocks in meshing engagement with each other, and a rod slidably mounted on the handle and operatively connected to a segment gear whereby a force exerted on the rod in one direction will actuate the mop head blocks to position the absorbent materials into impinging relation.

5. In a mop, a mop head comprising a pair of blocks, absorbent material fixed to the working faces of the blocks, a pair of plates pivotally mounted adjacent the ends thereof on the opposite sides of the blocks, a handle pivotally mounted on the plates, segment gears carried by the mop head blocks in meshing engagement with each other, and means mounted on the handle and connected to the segment gears adapted to actuate the gears and the mop head blocks to position the absorbent materials into impinging relation.

6. In a mop, a divided mop head, absorptive facings on the parts of the said head, transverse holding means to which the single parts of the said head are secured, means for causing the said parts to move together for compressing the said facings and to return to the normal position, and a mop handle secured to the said head so as to be capable of oscillation and relation thereto to the extent of approximately 180°.

7. In a mop as claimed in claim 5 an arm of resilient material pivotally mounted at one end on a plate of the pair of plates and having a series of openings adjacent the other end, and a pin extended laterally from the handle for releasable engagement with one of the series of the openings in the arm to support the handle in predetermined angular positions relative to the mop head.

8. In a mop, a mop head comprising a pair of blocks, absorbent material fixed to the working faces of the blocks, a pair of plates pivotally mounted adjacent the ends thereof on the opposite sides of the blocks to pivot-

ally mount the blocks in spaced relation to each other with the face of absorbent material extending in alinement with each other, a handle pivotally mounted on the plates, 5 means carried by the blocks arranged to transmit the movements of the blocks to each other, and means mounted on the handle and connected to the means carried by the blocks to actuate said latter means and the blocks to 10 forcibly position the absorbent materials into impinging relation to squeeze said materials.

9. In a mop, a mop head comprising a pair of blocks, absorbent material fixed to the working faces of the blocks, a carrier comprising a pair of members juxtaposed and 15 pivotally connected to the opposite sides of the blocks and a member pivotally mounted on the pair of members intermediate the pivotal connections thereof with the blocks, a sleeve mounted on the latter member arranged with a longitudinally extending recess, a handle engaged in the sleeve, means carried by the mop head blocks and arranged to transmit the movements of the blocks to each other, and a rod slidably mounted in the 20 sleeve recess to extend along the handle and connected to the means carried by the blocks, adapted by a force exerted thereon in one direction to actuate the blocks and position the absorbent materials into impinging relation.

25 10. A mop as claimed in claim 2, wherein the handle is tubular and the flexible members are extended through the handle with the manipulating grip connected to the flexible members exteriorly of the handle.

30 35 In testimony whereof I have affixed my signature.

THEODOR SENDLER.
